UNITED STATES PATENT OFFICE.

FRANK L. HARMON, OF BEVERLY, MASSACHUSETTS.

STRINGED MUSICAL INSTRUMENT.

960,317.

Specification of Letters Patent. Patented June 7, 1910.

Application filed July 7, 1905. Serial No. 268,741.

To all whom it may concern:

Be it known that I, FRANK L. HARMON, of Beverly, in the county of Essex and Commonwealth of Massachusetts, have invented 5 an Improvement in Stringed Musical Instruments, of which the following is a specification, reference being had to the accompanying drawings.

The object of this invention, is to attain 10 means for obtaining more freedom of vibration of a resonant body of a violin, and of other resonant devices in other stringed musical instruments, than has yet been attained.

15 The drawings show a new violin in plan in Figure 1, and in side elevation in Fig. 2.

Said resonant body A, cross-shaped steel support B, neck C and finger-board D fast to said support, tail-piece G, its string I on 20 stud H fast in said support, pegs J, chin-rest O and shoulder-pad N fast to said support, strings on the tail-piece and pegs, and bridge F, between the strings and the outside of said resonant device, are all shown 25 combined. Support B is secured to the edges of the body A, or resonant device, by screws E preferably fast in said body and loose in the holes in the support B. This connection to said body, at said edges only, 30 together with the fact that the ends of said body are free to vibrate, and are not held from vibrating by the hand shoulder and chin, when other violins are, shows that the applicant has attained the object of his invention.

35 Therefore, applicant claims his invention as follows:

1. In stringed musical instruments the combination of: a resonant device, a support 40 connected therewith and supporting said resonant device, and allowing the ends of said resonant device to be free to vibrate, means of attachment for strings connected with said support, strings attached to said means 45 of attachment, and a bridge between the strings and the outside of said resonant device.

2. In stringed musical instruments the combination of: a resonant device, a support connected therewith and supporting said resonant device, and allowing the ends of said resonant device to be free to vibrate, said support comprising neck, finger-board, chin-rest, shoulder-pad, and means of attachment for strings, strings attached to said means of attachment, and a bridge between the strings and the outside of said resonant device. 50

3. In stringed musical instruments the combination of: a hollow resonant device, a support connected with said hollow resonant device and supporting said resonant device, and allowing the ends of said resonant device to be free to vibrate, means of attachment for strings, strings attached to said means of attachment, and a bridge between the strings and the outside of said resonant device. 60

4. In stringed musical instruments the combination of: a hollow resonant device, a support connected with said hollow resonant device between the ends of said resonant device, and allowing the ends of said resonant device to be free to vibrate, means of attachment for strings connected with said support, strings attached to said means of attachment, and a bridge between the strings and the outside of said resonant device. 70

5. In stringed musical instruments the combination of: a hollow resonant device, a support connected with said hollow resonant device between the ends of said resonant device and supporting said resonant device, and allowing the ends of said resonant device to be free to vibrate, said support comprising neck, finger-board, chin-rest, shoulder-pad, and means of attachment for strings, strings attached to said means of attachment, and a bridge between said strings and the outside of said resonant device. 80

FRANK L. HARMON.
